DEGREASING MACHINE

Georg Edhofer and Georg Wolff, Munich, Germany, assignors to Dr. Alexander Wacker Gesellschaft für Elektrochemischer Industrie, G. m. b. H., Munich, Bavaria, Germany

Original application July 29, 1933, Serial No. 682,823. Divided and this application March 15, 1937, Serial No. 13,853. In Germany February 1, 1933

7 Claims. (Cl. 202—168)

This invention relates to the cleaning of metal articles, and has to do with means for immersing articles in a solvent for removing grease and dirt from such articles.

It is known to remove grease and dirt from metal articles by immersing them in a suitable solvent, in liquid or vapor form, the solvent being disposed within an open top tank through the top of which the articles are inserted and removed. The solvents used are such that the vapors thereof are of a higher specific gravity than air, such as trichlorethylene, perchlorethylene, or carbon tetrachloride. In practice, a suitable cooling device is provided in the upper portion of the tank for condensing the vapors generated from the liquid solvent, which is in the lower portion of the tank and is heated by suitable means. The cooling device condenses the solvent vapors so as to prevent escape thereof to the atmosphere. After the articles have been immersed in the solvent liquid or vapor, as the case may be, they are raised into the upper portion of the tank, above the vapor zone, where they are permitted to dry and are then removed from the tank. Due to the presence of the cooling device, the major portion of the tank is filled with cool air which takes up a small amount of the solvent vapors by diffusion. Under unfavorable conditions, particularly if there is a draft or the air in the tank is agitated, the cold air and the vapors diffused therein are apt to escape to the atmosphere, creating a disagreeable and objectionable odor.

When using apparatus of the character above referred to, the articles may be placed in suitable baskets or containers which are moved up and down in the tank with a view to facilitating cleaning of the articles. While this facilitates cleaning of the articles, it is open to the objection that it causes a certain amount of agitation of air in the tank, thus increasing the liability of escape to the atmosphere of air and solvent vapors from the tank. Also, this vertical up and down movement or reciprocation of the articles is not sufficient to assure thorough cleaning of hollow articles, and thorough removal therefrom of the solvent liquid when the articles are disposed in the upper portion of the tank for drying.

One of the main objects of our invention is to provide an apparatus suitable for cleaning articles in the manner above referred to, this apparatus embodying a tank which is effectively closed to the atmosphere during the cleaning operation so as to prevent escape from the tank of the vapors of the solvent liquid. A further

object is to provide an apparatus of this character in which the articles being cleaned may be rotated and thoroughly agitated within the tank, when the latter is closed, for effecting a thorough cleaning operation of the articles and facilitating drying thereof. Another object of our invention is to provide means whereby the portion of the tank containing the liquid solvent and the vapors thereof is closed to the atmosphere during removal of the cleaned articles and the placing in the tank of a second batch of articles to be cleaned. Further objects and advantages of our invention will appear from the detail description.

In the drawings:—

Figure 1 is a transverse vertical sectional view through the apparatus shown in Figure 2.

Figure 2 is a longitudinal vertical sectional view through an apparatus embodying our invention, taken substantially on line 2—2 of Figure 1.

This application is a division of our copending application for Means for degreasing and cleaning metal articles, Serial No. 682,823, filed July 29, 1933.

In the form of apparatus illustrated, casing 1c is provided, at the lower portion thereof, with two solvent liquid receiving tanks 1a and 1b, separated by a plate 1c. Each of the tanks is provided, at the bottom thereof, with a trough 1d in which is removably supported a sediment receiving tray 1e conveniently provided with lateral flanges which seat upon angle strips secured to the side walls of the trough, as shown. A cooling coil 46 is mounted in the upper portion of the casing above a trough 47 provided with a discharge tube 48 which delivers to tank 1b condensate which drips from the coil into the trough.

A shaft 11 is rockably mounted through side wall 1d of casing 1c, there being a stuffing box 12 about this shaft to prevent escape thereabout of solvent vapor from within the casing. Shaft 11 is bored out from its inner end and snugly receives a shaft 13 rotatably mounted through side wall 1e of casing 1c, there being a stuffing box 14 about shaft 13.

A sprocket wheel 19 is secured on shaft 13, within the casing 1c and adjacent wall 1e thereof, and is connected by a sprocket chain 20 to a sprocket wheel 21 secured on a stud 22 projecting from one end of a rectangular frame 23a. A stud 24 projects from the other end of frame 23a, and these two studs are rockably mounted in the outer ends of arms 25 provided at their other ends with collars 26 suitably secured upon shaft 11 for turning movement therewith.

Plates 49 extend upward and inward from the

front and back walls of the casing and are spaced at their upper edges from top plates 50 extending inward from said walls of the casing, the plates 49 and 50 and the adjacent portions of the casing 5 walls defining hoods open at their inner sides at 51 and communicating, by means of conduits 52 with the intake side of a blower 53 of known type. This blower and the motor 54 therefor are conveniently mounted on a bracket 55 suitably secured to the casing. Outlet fitting 56 of the blower may be connected, by a suitable conduit, to a space for discharging the air and vapor which may be withdrawn from the hood, the point of discharge being located exterior of the space in 15 which the apparatus is disposed.

The space between the hoods is closed by two cover members 58, each constituting a segment of a cylinder. The cover members are pivotally mounted on the casing at the lower ends of the 20 side walls of said members, at 59. Preferably, the cover members are interconnected by meshing pinions 60 secured to the pivots of the cover members for turning therewith, so that when either cover member is moved equal and corresponding movement will be imparted to the other cover member, in a known manner. Each of the cover members is provided with a suitable handle 61 for convenience in operating the same, and these handles are disposed in overlapping or 25 crossed relation when the cover members are closed, as shown in Figure 2. Each cover member 58 is provided, at the lower edge thereof, with a bead 62 which contacts a bead 63 at the upper end of the associated plate 49 and forms there- 30 with a substantially air tight closure, when the cover member is in closed position.

Two U-shaped straps or stirrups 64 are suitably secured to the depend from frame 23a. These stirrups receive the lower portion of a 40 perforated basket 65 disposed within the frame and provided with a removable cover 66. Upwardly and inwardly inclined arms 67 are suitably secured to the frame 23a at the ends thereof. These arms are of hooked shape at their upper ends and receive a slotted plate 68 which extends the length of frame 23a. A pressure screw 69 threads through plate 68 and has a loose nut connecting, in a known manner, to a pressure bar 70 which extends lengthwise of 50 basket 65 and its provided with depending lugs 71 which bear upon the top of cover 66 of the basket. This provides means for effectively securing the basket within the frame with expedition and facility.

55 A plate 72, in the form of a segment of a cylinder and curved on the same radius as the cover members 58, is suitably supported by arms 25 and segments 73, at each end of this plate, extend upwardly therefrom between the cooling 60 coil 46 and the adjacent supporting arm 25. When the frame 23a is in its uppermost position, shown in full lines, it is disposed within a cylinder generated by movement of either of the cover members 58 on its pivot. When the cover 65 members are moved into full open position, the beads 62 at the lower edges thereof contact beads 74 at the edges of plate 72 so as to form substantially airtight closures therewith, and the upper portions of the cover members fit snugly 70 against beads 63 of plates 49, as indicated by dotted lines in Figure 2. The basket 65 is thus enclosed in a housing closed to the interior of casing 1, when the basket is in its uppermost position and the cover members are in open position. This is advantageous as reducing possi-

bility of escape to the atmosphere of vapors from the interior of the casing. Any cool air containing diffused vapors, which may tend to escape through the top of the casing, is drawn into the hoods through openings 51 thereof, this air and the vapors contained thereby being delivered to a point remote from the space in which the apparatus is disposed, by means of the suction blower 53. The plate 72 is, of necessity, provided with suitable openings to accommodate the arms 25 and the sprocket chain 28. Any vapors which enter the space about the basket, through these openings, and diffuse into the air in this space, will be removed in the manner above set forth.

With basket 65 in the position shown in Figure 2, the covers 58 may be opened either partially or completely. With the covers partly open the suction means is effective for withdrawing air and diffused vapors from the upper portion of casing 1c from the zone about basket 65. This induces flow of air currents over and through the basket about the articles therein, which is conducive to increased rapidity in drying of the articles, particularly if the basket is rotated.

A crank handle 75 is suitably secured on the outer end of shaft 11 for turning the latter in desired direction. A counterweight 76, suitably secured to and depending from the crank handle 75, normally serves to hold the frame 23a in its uppermost position. By means of this crank handle 75, the shaft 11 may be turned so as to lower the basket into either tank 1a or tank 1b, as desired. A sprocket wheel 77 is secured on the outer end of shaft 13 and is connected by a sprocket chain 78 to a sprocket wheel 79 secured on one end of a shaft 80 rotatably mounted exterior of the casing and transversely thereof, in suitable bearing brackets 81 secured to the casing in a known manner. A crank handle 82 is secured to the other end of shaft 80 for imparting rotation thereto and thus rotating shaft 13. This provides means for rotating frame 23a, and the basket mounted therein, in any position of this frame within the casing.

A pipe frame 83 of U-shape in plan is disposed at one end of casing 1c, and arms 84 of this pipe frame extend lengthwise of the casing through tanks 1a and 1b. The portion of the respective arms 84 which is disposed within tank 1b is provided with slots or perforations 85, arms 84 being closed at the ends thereof within tank 1b. A gooseneck 86 connects the mid point of the bight portion of pipe frame 83 to the top of a boiler or still 87 disposed at one side of casing 1c. This still is enclosed by a suitable housing 88 and is provided with a concaved bottom wall 89 beneath which is disposed suitable heating means, such as a gas burner 90 of known type, within the lower portion of the housing. A strip 91 is suitably supported in spaced relation to the upper portion of plate 1c and defines therewith an overflow opening from tank 1a to tank 1b. An overflow pipe 92, provided with a suitable control valve 93 of known type, opens into tank 1a below the upper edge of plate 1c. This pipe is connected, at its other end, to a drain pipe 95, provided with a suitable control valve 96 of known type, this drain pipe opening into the still through the bottom wall 89 thereof.

After the basket 65, containing the articles to be cleaned, has been suitably secured in frame 23a, and the cover members 58 have been closed, shaft 11 is turned so as to move the basket into the dotted line position of Figure 2, thus immers-

ing the articles in the liquid solvent within tank 7a. The basket may be rotated, in this position, to facilitate cleaning of the articles. The basket may then be positioned within the tank 7b, by 5 turning shaft 11 in the opposite direction, and again rotated with the articles immersed in the liquid of tank 7b, thus thoroughly rinsing the articles and removing therefrom any particles of grease or other foreign materials which may 10 not have been removed by the first treatment in tank 7a. After the articles have been thoroughly rinsed, the shaft 11 is turned into position to dispose the basket 65 in its uppermost position, after which the articles are dried and the basket is 15 removed and replaced by a second basket containing articles to be cleaned, in the manner previously described. The liquid solvent in tank 7a is heated by the hot vapors passing through the arms 84 of the pipe frame 83, and the liquid 20 solvent within tank 7b is heated by the hot solvent vapors projected thereto through the slits 85. These hot vapors are condensed by the liquid in tank 7b and thus serve continuously to supply pure solvent liquid to this tank, while also 25 heating the liquid on both tanks in the manner stated. The excess liquid supplied to tank 7b overflows into the tank 7a so as to replenish the supply of liquid therein, and the excess liquid from tank 7a is returned to the still where it is 30 distilled, the pure solvent vapors being delivered to tank 7b, as previously described. The drain pipe 95 provides convenient means for draining off, as required, grease and other impurities which, if permitted to collect in considerable 35 quantity within the still, might result in overheating and decomposition of the liquid solvent. Grease and other foreign materials which collect in the lower portions of the tanks 7a and 7b are removed by means of the collecting trays 7e 40 previously referred to.

As will be understood by those skilled in this art, changes in construction and arrangement of parts of the invention may be resorted to without departing from the field and scope of the same, and we intend to include all such variations, as fall within the scope of the appended claims, in this application, in which the preferred form only of our invention is disclosed.

50. What we claim is:

1. In apparatus of the character described, an open top casing for containing in its lower portion a solvent, covers for the top of the casing, means for supporting within the casing articles 55 to be cleaned, means operable exteriorly of the casing for moving said supporting means from the upper portion of the casing to the lower portion thereof and returning the supporting means to the upper portion of said casing when the covers are closed, said casing comprising suction 60 hoods including plates projecting inward adjacent the top of said casing into proximity to said covers, a plate carried by said supporting means movable therewith and disposed there- 65 beneath when said supporting means is in its upper position, said covers forming with said casing and said plates thereof an enclosure over and about said supporting means, when the latter is in its upper position and said covers are 70 closed, said covers when in open position forming with said plates and the plate carried by said supporting means an open top enclosure extending beneath and about said supporting means and substantially closed to the lower portion of said 75 casing, when said supporting means is in its

upper position, and means for drawing off solvent vapors from said suction hoods.

2. In apparatus of the character described, an open top casing for containing in its lower portion a solvent, covers for the top of the casing, means for supporting within the casing articles to be cleaned, means operable exteriorly of the casing for moving said supporting means from the upper portion of the casing to the lower portion thereof and returning the supporting means to the upper portion of said casing when the covers are closed, said casing comprising suction hoods opening at their inner sides into said casing adjacent the top thereof having lower plates projecting inward from the sides of said 15 casing into proximity to said covers, a plate carried by said supporting means movable therewith and disposed therebeneath when said supporting means is in its upper position, said latter plate and said covers comprising segments of a 20 cylinder and having the same radius of curvature, said covers forming with said casing and said hood plates an enclosure over and about said supporting means, when the latter is in its upper position and said covers are closed, said 25 covers when in open position extending from said hood plates to the plate carried by said supporting means and forming with the latter plate and said hood plates an open top enclosure extending beneath and about said supporting 30 means, when the latter is in its upper position, and means for drawing off solvent vapors from said suction hoods.

3. In apparatus of the character described, an open top casing for containing in its lower portion a solvent, suction hoods at the top of the casing and open thereto at their inner sides, means for supporting within said casing articles to be cleaned, said supporting means being movable from an upper position to a lower position and 40 vice versa, covers for said casing comprising segments of a cylinder and having the same radius of curvature, said covers extending above said article supporting means in the upper position thereof, said hoods having lower plates extending from the sides of said casing into proximity to said covers and forming therewith and with the upper portion of said casing an enclosure over and about said supporting means, when the latter is in its upper position and said covers 50 are closed, a plate movable with said supporting means comprising a segment of a cylinder having the same radius of curvature as said covers and extending beneath said supporting means in the upper position of said supporting means, 55 said plate and the upper portion of said casing forming with said covers an open top enclosure about and beneath said supporting means, when the latter is in its upper position and said covers are in full open position, and means for drawing 60 off solvent vapors from said suction hoods.

4. In an apparatus of the character described, a casing for containing in its lower portion a solvent, suction hoods projecting inward from opposite sides of said casing adjacent the top 65 thereof each comprising an upper plate and a lower plates spaced apart at their inner edges and defining a suction opening into the top of said casing, said lower plates defining between their inner edges an opening into said casing 70 below said hoods, cooperating covers for the latter opening extending into said casing and pivoted for movement in proximity to and about axes parallel with the inner edges of said lower plates, article supporting means within said casing mov- 75

able into a lower position and an upper position in alignment with said opening, a plate carried by and movable with said supporting means and disposed therebeneath in the upper position of 5 said supporting means, said covers being of such extent as to form with said hood plates and the upper portion of said casing an enclosure about the upper portion of said supporting means, in the upper position of the latter and when said 10 covers are closed, while forming with said lower hood plates and the plate carried by said supporting means an open top enclosure beneath and about said supporting means, when the latter is in its upper position and said covers are in 15 full open position, and means for drawing off solvent vapors from said suction hoods.

5. In an apparatus of the character described, a casing for containing in its lower portion a solvent, suction hoods projecting inward from 20 opposite sides of said casing adjacent the top thereof each comprising an upper plate and a lower plate spaced apart at their inner edges and defining a suction opening into the top of said casing, said lower plates defining between 25 their inner edges an opening into said casing below said hoods, closure means for the latter opening comprising covers movable therethrough in proximity to the inner edges of said lower plates into open and closed positions, article sup- 30 porting means within said casing movable into a lower position and an upper position in alignment with said opening, a plate carried by said article supporting means and disposed therebeneath in the upper position of said article sup- 35 porting means, said covers when closed forming with said lower plates an enclosure over and about said supporting means in the upper position thereof, said covers when open forming closures with the inner edge portions of said 40 lower plates and extending therefrom downward about said supporting means into contact with said plate carried thereby, the latter plate and said covers defining about said supporting means an open top space in communication with said 45 suction openings, when said supporting means is in its said upper position, and means for withdrawing solvent vapors from said suction hoods.

6. In an apparatus of the character described, a casing for containing in its lower portion a 50 solvent, suction hoods at opposite sides of the casing adjacent the top thereof and opening at their inner sides into said casing, each of said

hoods comprising a lower plate projecting inward from the adjacent side wall of the casing, said plates defining between their inner edges an opening into said casing below said hoods, closure means for the latter opening comprising covers 5 movable therethrough in proximity to the inner edges of said plates into open and closed positions, article supporting means within said casing movable into a lower position and an upper position 10 in alignment with said opening, a plate carried by said article supporting means disposed therebeneath in the upper position of said article supporting means, said covers when open forming closures with the inner edge portions of said plates and extending therefrom downward about 15 said supporting means into contact with said plate carried thereby, the latter plate and said covers defining about said article supporting means an open top space in communication with the inner sides of said hoods, when said support- 20 ing means is in its said upper position, and means for withdrawing solvent vapors from said suction hoods.

7. In an apparatus of the character described, a casing for containing in its lower portion a solvent, suction hoods projecting inward from 25 opposite sides of said casing adjacent the top thereof and open thereto at their inner sides, said hoods defining between them an opening into said casing below said hoods, closure means for 30 said opening comprising covers movable therethrough in proximity to the inner sides of said hoods, article supporting means within said casing movable into a lower position and an upper position in alignment with said opening, a plate carried by said article supporting means disposed 35 therebeneath in the upper position of said article supporting means, said covers when closed forming with said hoods an enclosure over and about said supporting means in the upper position 40 thereof, said covers when open forming closures with the lower inner edge portions of said hoods and extending therefrom downward about said supporting means into contact with said plate carried thereby, the latter plate and said covers 45 defining about said article supporting means an open top space in communication with the inner sides of said hoods, when said supporting means is in its said upper position, and means for withdrawing solvent vapors from said suction hoods. 50
